Merwyn C. Teague, Sparta, N. J., assignor to
United States Rubber Company, New York,
N. Y., a corporation of New Jersey

Application May 1, 1953, Serial No. 24,802

Term of patent 3½ years

(Cl. D7—4)

To all whom it may concern:

Be it known that I, Merwyn C. Teague, a citizen of the United States, residing at Sparta, in the county of Sussex and State of New Jersey, have invented a new, original, and ornamental Design for a Foothold, of which the following is a specification, reference being had to the accompanying drawing, forming a part thereof.

Fig. 1 is a side elevational view of one side of the foothold;

Fig. 2 is the side elevational view of the opposite side of the view shown in Fig. 1;

Fig. 3 is a top view of the foothold; and
Fig. 4 is a bottom plan view of the foothold.

I claim:

The ornamental design for a foothold, as shown.
